UNITED STATES PATENT OFFICE.

DAVID P. PERRY, OF CHICAGO, ILLINOIS.

ELECTRIC HORN.

No. 907,399.

Specification of Letters Patent.

Patented Dec. 22, 1908.

Application filed January 27, 1906. Serial No. 298,117.

To all whom it may concern:

Be it known that I, DAVID P. PERRY, a citizen of the United States of America, and resident of Chicago, Illinois, have invented a certain new and useful Improvement in Electric Horns, of which the following is a specification.

My invention contemplates an improvement on the electric horn disclosed in my prior application Serial No. 285,766, filed November 3, 1905.

Generally stated, the object of my present invention is to provide an improved and highly efficient electric horn.

Special objects of my present invention are the provision of means for protecting the sound-producing diaphragm against moisture, dust and the like, which might enter the mouth of the horn; the provision of an improved construction and arrangement for operating the sound-producing diaphragm; the provision of an improved construction and arrangement for clamping and holding the sound-producing diaphragm and other parts in place; and the provision of certain details and features of improvement tending to increase the general efficiency and effectiveness of a device of this particular character.

To the foregoing and other useful ends, my invention consists in matters hereinafter set forth and claimed.

In the accompanying drawings, Figure 1 is a longitudinal section of an electric horn embodying the principles of my invention. Fig. 2 is a detail of one of the diaphragm clamping rings. Fig. 3 is a detail view of the inner or back surface of the metal sound-producing diaphragm. Fig. 4 is a detail sectional view of a portion of the electro-magnetic mechanism for operating the diaphragm, and is a section on line 4—4 in Fig. 5. Fig. 5 is a detail section on line 5—5 in Fig. 1. Fig. 6 is a cross-section on line 6—6 in Fig. 1. Fig. 7 is a cross-section on line 7—7 in Fig. 1. Fig. 8 is a horizontal detail section on line 8—8 in Fig. 1. Fig. 9 is a detail section on line 9—9 in Fig. 6. Fig. 10 is a top plan view of the electro-magnets and associated parts shown in Figs. 1 and 6.

As thus illustrated, my invention comprises a resonator A made of sheet-metal and fastened into the end of the coupling ring a. Said coupling ring is provided with a threaded rear portion adapted to screw into the internally and externally threaded diaphragm

supporting-ring B. This ring B has a shoulder b against which the sound-producing diaphragm C is clamped or held, this diaphragm being provided at its edge with rubber or other insulating material c, and at its center with a metallic reinforce or disk-like portion c'. The main sound-producing diaphragm is held in place by an intermediate or separating ring D, an auxiliary diaphragm E, and a clamping ring F, arranged in the order specified. Thus it will be seen that the two diaphragms are slightly separated from each other, and that the three elements, namely the diaphragms and the separating ring, are all clamped in place by the peripherally threaded clamping ring F, which latter is screwed into the threaded bore of the ring B. This auxiliary diaphragm E has its edges provided with rubber or other insulating material e, and is preferably composed of mica or other suitable material. In this way, the vibrations produced by the metallic diaphragm C are modified by the auxiliary diaphragm,—that is to say, the tone is softened and rendered more pleasing to the ear. Furthermore, this auxiliary diaphragm serves to seal the passage leading to the main diaphragm, and to thus protect the said main or metallic diaphragm against exposure to moisture or dust or the like which may enter the horn.

A bracket-plate G is preferably secured to the back of the ring B, and a pair of electro-magnets H are secured upon this bracket-plate. An armature mounting I is provided at its end with an armature i, which latter is operated by the said electro-magnets. The contacts i', i'', operated by the said armature, serve to interrupt the flow of current through the said electro-magnets, whereby the mechanism as a whole constitutes a buzzer for rapidly vibrating the reciprocating rod or tapper J. This electro-magnetically operated tapper J is supported in a bearing j, and also in an opening extending through the bracket-plate G, as shown more clearly in Fig. 8. A spring j' is applied in such a manner as to tend normally to hold the forward end of the tapper out of engagement with the diaphragm C, and a spring g' assists the said spring j' in keeping the armature i in a normal or retracted position. The flexible current conductors or insulated circuit wires K are led through an opening k in the rear of the sheet-metal cap L, which latter is screwed upon the ring B to inclose the electro-mag-

netic operating mechanism. A clamping device M is secured to the side of the sheet-metal cap L for the purpose of securing the horn to any suitable support. When sufficient electric current is caused to flow through the electro-magnets H, a rapid reciprocation of the diaphragm tapper results therefrom, and the rapid vibration thus given the said main diaphragm C is communicated through the inclosed body of air to the auxiliary diaphragm E. This results, of course, in the establishment of a rapid vibration of air in the resonator A, with the further result that the horn gives forth a loud and pleasing tone.

Thus it will be seen that I provide an improved and highly efficient electric horn, which can be easily taken apart and put together, which is adapted to produce a good and clear tone, and which has its sound-producing means fully protected against moisture or dust or anything else of like character which might enter the mouth of the horn.

What I claim as my invention is:

- 25 1. An electric horn comprising a resonator, a coupling ring secured to the smaller end thereof, a diaphragm supporting rim separably secured to said coupling ring, a pair of diaphragms, separating means therebetween, and a tapper for rapidly beating one of said diaphragms.
- 30 2. An electric horn comprising a resonator, a coupling ring secured to the smaller end thereof, a diaphragm supporting rim separably secured to said coupling ring and provided with a shoulder, a pair of diaphragms, separating means therebetween, one of said diaphragms abutting against said shoulder, and a bracket plate secured to the back of said diaphragm and supporting ring, a tapper for rapidly beating one of said diaphragms, and electro-magnetic means for operating said tapper.

3. An electric horn comprising a resonator, a coupling ring secured to the smaller end thereof, a diaphragm supporting rim separably secured to said coupling ring and provided with a shoulder, a pair of diaphragms one of which is formed from metal and provided with a centrally located reinforcing plate, separating means between said diaphragms, said reinforced diaphragm abutting against said shoulder, and a tapper for rapidly beating the center of said reinforced diaphragm.

4. An electric horn comprising a resonator, a coupling ring secured to the smaller end thereof, a diaphragm supporting rim separably secured to said coupling ring and provided with a shoulder, a pair of diaphragms one of which is formed from metal and provided with a centrally located reinforcing plate, separating means between said diaphragms, said reinforced diaphragm abutting against said shoulder, a tapper for rapidly beating the center of said reinforced diaphragm, and electro-magnetic means for operating said tapper.

5. An electric horn comprising a resonator, a coupling ring secured to the smaller end thereof, a diaphragm supporting rim separably secured to said coupling ring and provided with a shoulder, a pair of diaphragms one of which is formed from metal and provided with a centrally located reinforcing plate and the other comprising a mica plate, separating means between said diaphragms, said reinforced diaphragm abutting against said shoulder, and a tapper for rapidly beating the center of said reinforced diaphragm.

Signed by me this 25th day of Jany. 1906.

DAVID P. PERRY.
